UNITED STATES PATENT OFFICE.

PAUL E. HERRMANN, OF NEW YORK, N. Y.

ELECTRICAL ATTACHMENT PLUG.

Application filed November 11, 1922. Serial No. 609,381.

To all whom it may concern:

Be it known that I, PAUL E. HERRMANN, a citizen of the United States, and resident of the city of New York, in the county of

5 Kings and State of New York, have invented certain new and useful Improvements in Electrical Attachment Plugs, of which the following is a specification.

The present invention relates to improvements in electrical connectors, and more particularly to screw plugs.

The main object of the invention is to provide an attachment for screw plugs, whereby a drop light or other suitable electric device, carried by the conductors connected to the plug, may be adjustably held at any desired distance from the said plug.

Another object of the invention is to produce a conductor of the character mentioned which is simple in construction, efficient in operation, durable in use and which is capable of manufacture on a commercial scale, or in other words one which is not so difficult to make as to be beyond the reasonable cost of such a contrivance.

A further object of the invention is to so construct the attachment that it may be mounted upon screw plugs without necessitating changes in the construction of the latter.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

45 One of the many possible embodiments of the invention is illustrated in the accompanying drawings, in which:

Figure 1 is an elevation of a screw plug and the attachment, showing the same in position in an ordinary lamp socket, in combination with an electric heater in operative relation thereto; Fig. 2 is a front elevation, partly in section, of a screw plug and the attachment, on a larger scale; and

55 Fig. 3 is a side elevation of the attachment.

In the drawings, the numeral 10 indicates

a screw plug, it comprising an insulating base 11, carrying two electric terminals 12 and 13. Conductor cords 14 are connected with these terminals in the usual manner. On the base is rotatably mounted a screw shell 15, mounted on an insulating sleeve 16. The screw shell is in electric contact with a screw-threaded bushing 17, that is fixed in any suitable manner to the base 11, said bushing being in electrical engagement with the terminal 13. The screw shell is held in position upon the base by an insulating bushing 18, having screw threads 19 meshing with those of the bushing 17. The conductor cords extend through the bushing 18, as usual in constructions of this type. Thus far described, the construction and operation of the elements are well known, so that a further detailed description thereof seems to be unnecessary.

The attachment comprises a plate member 20, having a central hole 21, through which the screw-threaded bushing 17 extends, said plate member abutting against the underside of the sleeve 16 and being held in position upon the screw plug by the insulating bushing 18. To the plate member 20 is attached in any suitable manner a bail-shaped element 22, projecting below the said plate member, and being centrally provided with an eye 23, to which is hooked a pulley block 24, carrying a small pulley 25.

The conductor cords are connected, in the case illustrated in the drawings, to an electric heater 26, the screw plug being in engagement with an ordinary lamp socket 27 on a bracket 28, the latter being attached to a wall 29, or to any other suitable support. To the heater is secured one end of a cord 30, which is extended over the pulley 25 and carries at its other end a counter weight 31. By shifting this counter weight, the heater may be held in any desired position in relation to the screw plug.

It is obvious that, while herein a heater has been described as being attached to the conductor cords any other electrical device may be connected therewith, without departing from the invention, which lies mainly in the provision of an attachment to screw plugs, in the form of a pulley, over which may be extended a cord, one end of which is secured to the electrical device connected to the conductor cords, and upon the other end of which is mounted a counterweight.

It is also obvious that, while herein a

specific screw plug has been described, the attachment is applicable to others just as well.

What I claim is:—

- 5 1. A screw-plug comprising an insulating base, electric terminals carried by said base, conductor cords connected to said terminals, a screw shell in electrical engagement with one of said terminals, said shell being 10 mounted to rotate on said base, an insulating sleeve attached to said screw shell, a screw-threaded bushing fixed to said base, a plate member provided with a hole through which said bushing extends, a screw-threaded insulating bushing in engagement with said first-mentioned bushing for holding said plate member against said insulating sleeve, and a pulley depending from said plate member.
- 15 2. A screw-plug comprising an insulating base, electric terminals carried by said base,

conductor cords connected to said terminals, a screw-shell in electrical engagement with one of said terminals, said shell being 20 mounted to rotate on said base, an insulating sleeve attached to said screw shell, a screw-threaded bushing fixed to said base, a plate member provided with a hole through which said bushing extends, a screw-threaded insulating bushing in engagement with said first-mentioned bushing for holding said plate member against said insulating sleeve, and a pulley depending from said plate member.

Signed at New York, in the county of New York, and State of New York, this 23rd day of October, A. D. 1922.

PAUL E. HERRMANN.
